PLANT FOR PULVERIZING AND BURNING
COAL

Benjamin Graemiger, Zurich, Switzerland

Application January 6, 1936, Serial No. 57,822
In Switzerland January 8, 1935

3 Claims. (Cl. 83—93)

The invention relates to a method for operating pneumatic pulverizers in which the grinding operation is effected by a stream of gaseous operating medium (as a rule air). The work producing stream is formed by the expansion of the operating medium in one or more suitably shaped nozzles. The operating medium must be compressed and in most cases a heating also takes place after the compression whereby the energy, 10 that is to say the velocity of the stream, which is set free as a result of the expansion is increased. When a predetermined energy of expansion is to be converted in the pulverizer the work of compression becomes the smaller the 15 higher the temperature of the operating medium, whether a lower pressure is produced or the quantity of operating medium selected is smaller. Heating operating medium also promotes the drying of the material to be ground which is generally 20 damp, during the pulverizing operation and by the drying the capacity of the material to grinding is also improved in most cases. The heating of the compressed operating medium is consequently advantageous for numerous reasons in most cases. To the advantages of the pneumatic pulverizer, 25 in connection with which there is to be particularly emphasized the omission of movable constructional parts in the pulverizer itself, there is opposed in many cases and even when the heating of the operating medium is carried to a far-reaching extent, a high requirement of energy for the compression of the gaseous operating medium as compared with the requirement of energy by pulverizers of a different type.

The compression energy is taken up by a motor 35 which drives the compressor. In most cases this is an electric motor, occasionally also a steam turbine.

The invention has for its object to reduce the 40 cost for compressing the operating medium and thus for the pulverizing. The invention resides therein that into the gaseous operating medium, of which at least one part serves for the operation of the pulverizer, there is supplied, by compression and heating, a larger amount of energy 45 than is necessary for the operation of the pulverizer and that the excess energy is utilized in a power engine which drives the compressor. In this manner it becomes possible to carry out the compression work necessary for the operation of 50 the pulverizer at least in part by heat supplied to the operating medium and thus wholly or partly to effect an economy in the consumption of mechanical or electrical energy. In most cases the 55 price for heat and the price for mechanical or electrical energy are in such a relation that the expense involved for the pulverizing according to the method according to the invention is considerably less than according to one of the methods 60 hitherto usual. Frequently also the heat which

has been introduced may again be utilised so that it is possible to effect a pulverizing which is practically costless.

The necessary excess of energy may be produced in that a quantity of operating medium greater than that necessary for the operation of the pulverizer is compressed and heated and the excess of operating medium is expanded in a power engine which drives the compressor. This method becomes particularly advantageous when the 10 heat still contained in the excess of operating medium after expansion can be made capable of use in any suitable manner (under circumstances also outside the pulverizing plant). A partial utilisation is obtained for example when 15 this waste heat is supplied to the compressed operating medium by means of a heat exchanger. In the case of coal-dust furnace installations wherein the coal-dust produced is blown directly into the furnace the expanding excess of operating medium can be introduced into the furnace 20 as secondary air. There is then not only supplied to the furnace the heat contained in the part of the operating medium which flows through the pulverizer but the total heat supplied to the 25 system.

Such a plant becomes particularly simple when the whole of the combustion air is supplied by the compressor, of which one part serves as the operating air for the pulverizer and thus as the primary air, and the other part after expansion has taken place as the secondary air. A separate blower together with a driving motor for the secondary air then becomes unnecessary.

The excess energy may also be obtained by compressing the operating medium serving for the operation of the pulverizer to a pressure which is higher than that necessary for operating the pulverizer and after heating expanding it in a power engine serving to drive the compressor, at least approximately to the pressure necessary for operating the pulverizer. In this connection it may occur that the operating medium after expansion has taken place in the power engine is still too hot to be capable of being used for operating the pulverizer. In this case heat is withdrawn from the operating medium before it enters the pulverizer, whilst naturally endeavours are always made to again use this withdrawn heat in any suitable manner. This may preferably be effected in that the withdrawn heat is supplied to the operating medium between the compressor and the power engine.

In the case in which at least a part of the operating medium is separated beyond the pulverizer, from the fine material produced, in a separator, this part may also be used for heating the operating medium between the compressor and the power engine. Naturally any other use of this waste heat is possible, if desired also in 60 65 70 75 80 85 90 95 100

another plant which has no relation with the grinding plant.

There may also be used a quantity of operating medium which is larger than that necessary for the operation of the pulverizer and to compress this to a pressure higher than that necessary for operating the pulverizer. The part of the operating medium necessary for the operation of the pulverizer then expands in the power engine driving the compressor to the pressure necessary for the operation of the pulverizer, whilst the excess of operating medium expands in a power engine to a pressure lower than that necessary for operating the pulverizer. The expanded excess operating medium can then again be used for heating the operating medium between the compressor and the power engine.

When the heat supplied to the system is not sufficient for obtaining the energy for compression a motor can support the power engine in which the operating medium expands. It is particularly advantageous to include in the flow of the operating medium an additional compressor which is then in turn driven by a motor of any suitable type. Auxiliary energy may also be supplied to the system in that a compressed gaseous medium of any suitable type is introduced into the operating medium supplied by the main compressor. This may be effected, for example, in that an auxiliary compressor driven in any suitable manner, operates in parallel with the main compressor, or a medium, in vapour form, under pressure is supplied. The supply of such an additional medium may be effected before or after heating the operating medium. Such an introduction of additional medium particularly arises during the period of starting such a plant.

In the accompanying drawing there are shown by way of example two diagrams for the method according to the invention.

Figs. 1 and 2 relate to the case in which a quantity of operating medium greater than that necessary for operating the pulverizer is compressed to the pressure necessary for operating the pulverizer and heated.

In these diagrams the same references indicate the same part. 1 is a driving motor of any suitable type, 3 the main compressor coupled to the power engine 4 (in which the operating medium expands). 5 is the pneumatic pulverizer to which the operating medium is supplied through the pipe 10, whilst the material to be pulverized is supplied through the pipe 15 and the dust produced flows off with the operating medium (expanded in the pulverizer) through the pipe 14. 7 is the suction pipe of the main compressor 3. In the admission pipe 9 of the expansion power engine 4 is included the device for heating the operating medium which in Fig. 1, is constructed as a surface heat exchanger 11, 12, whereas the operating medium in the case of Fig. 2 is heated in a combustion chamber 13 subjected to the pressure of the operating medium. In Fig. 2, there is shown an auxiliary compressor 2, arranged in front of the main compressor, and 6 is the suction pipe of the auxiliary compressor 2. In Fig. 1 there is included in the pipe 8 also an additional heat exchange device 16, 17 through which the heat withdrawn from the expanded operating material is conducted into the compressed operating medium.

As regards the diagrams the following may also be mentioned in detail by way of explanation. Assuming that the temperature of the operating medium, which flows through the pul-

verizer, may not be as high as the temperature of the part which flows through the expansion power engine 4, there is effected in Fig. 1 a branching of the pipe 10 between the heat exchanger 16, 17 and the heating device 11, 12. It is also possible to branch the supply pipe to the pulverizer from an intermediate stage of the heat exchanger 11, 12 as is indicated in Fig. 1 by the broken line 10a. The coupling between the motor 1 and the group, consisting of the compressor 3 and the power engine 4, may be effected directly or through the interposition of a transmission gear. The heating of the operating medium in the heat exchangers 11, 12 may be effected, for example, by the waste heat of a steam generator.

In Fig. 2, the heating of the operating medium is effected by the combustion of any supply found in the combustion chamber 13 which is arranged between the pipes 8 and 9. 31 indicates the supply pipe for the fuel. In front of the combustion chamber a first portion of the operating air is passed through the pipe 38 and behind the combustion chamber there is branched a second portion for the pulverizer through the pipe 39. The two pipes are combined into the pipe 10. In the pipe 38 is included a regulating member 40 by which the temperature of the mixture in the pipe 10 can be influenced. The driving motor 1 is here not coupled mechanically to the group 34 but it drives the additional auxiliary compressor 2. Such a compressor could also be included in the pressure pipe 8, further an additional compressor could be arranged in parallel with the main compressor. By the pipe 41, indicated in broken lines, is indicated an alternative by means of which an additional operating medium is supplied to the power engine 4. When for example 4 is a hot air turbine, then water vapour could be supplied through 41 for supporting the operation by providing for this purpose an auxiliary nozzle. Such an auxiliary device may also be provided adjacent an actual driving motor so as to provide supplementary means when starting or when the plant is subjected to an extremely high load. For the internal combustion in the chamber 3, there may be selected a solid, liquid, gaseous, or mixed fuel. The heating may also be so effected that a first stage takes place by indirect heating (Fig. 1) and a second stage by internal heating. The use of one part of the waste heat of the exhaust air of the power engine 4 for heating the air in the pipe 8, may naturally also be carried out within the scope of the diagram in Fig. 2.

For completing the explanation as to the method of operation in Figs. 1 and 2, there will be hereinafter set out numerically a first example. In a furnace plant with direct blowing in of coal dust produced in a pneumatic coal mill, the amount of coal dust produced and burnt is assumed to be 1 ton/hour. The energy to be applied between the expansion nozzle and the dust air outflowing from the mill is 24 kw. which corresponds with a coal capable of being ground moderately well. At a temperature in front of the nozzle of 250° C. and a pressure ratio of 1.26 there is obtained a quantity of operating air of 2580 kg./hour. The total quantity of air necessary for the combustion is 12900 kg./hour (10 normal cubic meters/kg. coal). The compressor 3 supplies this total quantity of air, having regard to the resistance in front of and behind the mill at a pressure ratio of 1.30. Assuming 20° C. in the suction pipe 7, and a compression efficiency 75

of 72% calculated on the adiabatic basis, the compression output is 115 kw. Through the power engine 4 there flow 12900-2580=10320 kg. air/hour. The temperature in the pipe 9 amounts to 500° C. Having regard to the resistances in front of and behind the power engine, there is calculated for the expansion only a pressure ratio of 1-263. With an efficiency calculated on the adiabatic expansion of 80% there is obtained an output of 115 kw. so that the driving motor is entirely unloaded. Without taking up external mechanical or electrical energy, the grinding and conveying of the coal dust and in addition the degree of pressure for overcoming the resistances are effected in the air heater and in the burner. The heat which is taken up is completely utilized in the furnace 42 (having an outlet 43) both with the primary air and also with the secondary air. This (in the case of the diagram Fig. 2) has in the pipe 34 a temperature of 460° C. The primary air is cooled during the grinding operation only to such an extent as is necessitated by the drying and heating of the coal. For both, however, it is no longer possible to supply the corresponding heat consumption in the furnace. It is well known that the operation of coal-dust furnaces is promoted to a high degree by high temperatures of the combustion air which is supplied. In the case of a steam generator it is in general also very advantageous to mount in the system an air pre-heater as subsequent heating surface. Should the temperatures here assumed lead to undesirable conditions in the arrangement of the subsequent heating surfaces of the heat generator, then the upper stage of the heating can be carried out separately either by an additional indirect heating or by internal combustion.

Under usual conditions of operation the compressor would bring 2580 kg./hour operating air to the pressure ratio 1.30 and then take up an output of 27 kw. measured at the terminals of the driving electric motor. If, however, it is desired to effect an air preheating to the same extent, as occurs in this example, there would also be the output of a secondary air blower amounting to about 12 kw. The total gain thus amounts to about 39 kw. In the present example there is assumed a single stage rotary compressor and a single stage and single-bladed turbine. In many cases, however, there exists between heat and current price a ratio which is still more favorable for the method according to the invention. This particularly occurs when the heat consumption can be supplied wholly or partly (particularly the low temperature stages) by waste heat of any type. Particularly favorable is the case where the heat introduced into the system can be used in any way. This for example is the case when the air charged with fuel passing out through the pipe 14 is conducted into a furnace chamber.

The carrying out of the method leads in most cases to the use of a single stage hot air turbine with a single or multi-stage compressor. These engine-groups can be constructed in a particularly advantageous manner in that the suitable speed of rotation for the turbine and the compressor are well tuned to one another. There is consequently obtained a minimum of weight and space requirement. This is particularly the case when being used on vehicles of any kind of importance. The regulation of these groups is very satisfactory. For influencing the operation there arise for example: The variation of the ad-

mission temperature of the turbine, the variation of the nozzle cross section at the pulverizer, the variation of any auxiliary energy that may be supplied.

The method according to the invention is in no way bound to the type of engines which are used for compression and expansion. Also there is no limitation to the selection of any auxiliary motor that may be required and in the method and manner of the introduction of the additional energy into the system. The construction of the device for heating the operating medium may have any imaginable forms. The pneumatic pulverizer may have any form of construction. The circuits and devices for the heat transmission may depart from the examples here shown. As regards the pressure and temperature between the total quantity of operating medium and the part flowing to the pulverizer there is no limitation. In particular it is to be emphasized that also behind the pulverizer there may obtain an appreciable pressure above atmospheric pressure, as is for example the case in connection with fuel pulverizing in combination with a furnace operating under pressure. There is no restriction as regards either the material to be pulverized or the gaseous operating medium to be used.

What I wish to secure by United States Letters Patent is:

1. A pulverizing plant which comprises in combination a compressor compressing a gaseous operating medium, means for heating the compressed operating medium, a power engine in which a part of the compressed and heated operating medium expands and which drives said compressor, and a pneumatic pulverizer in which the other part of the compressed and at least in part heated operating medium expands, and means for dividing the heated gas into two parts and for conducting one part to the pulverizer and the other part to the engine.

2. A pulverizing plant which comprises in combination a compressor compressing a gaseous operating medium, means for heating the compressed operating medium, a power engine in which a part of the compressed and heated operating medium expands and which drives said compressor, a pneumatic pulverizer in which the other part of the compressed and at least in part heated operating medium expands, means for dividing the heated gas into two parts and for conducting one part to the pulverizer and the other part to the engine and means for transferring heat contained in the part of the operating medium expanded in said power engine into the operating medium leaving said compressor.

3. A plant for pulverizing and burning coal which comprises in combination a compressor compressing air, means for heating the compressed air, a power engine in which a part of the compressed and heated air expands and which drives said compressor, a pneumatic coal pulverizer in which the other part of the compressed and fully or partly heated air expands, means for dividing the heated gas into two parts and for conducting one part to the pulverizer and the other part to the engine, a furnace, means for blowing the air expanded in said pulverizer as primary air together with the pulverized coal directly into said furnace, and means for blowing the air expanded in said power engine as secondary air into said furnace.

BENJAMIN GRAEMIGER.
